ABSTRACT OF THE DISCLOSURE

A straight-bar knitting machine which can change from rib to plain knitting. The machine has vertical frame needles selected ones of which are rendered inoperative for rib knitting, and horizontal machine needles positionable in the spaces vacated by imperorative frame needles. Each machine needle comprises an outer element having a yarn-receiving and loop-forming hook and an operating butt, and a pair of inner loop-retaining elements which are longitudinally movable together relatively to the outer element and formed with side-by-side operating butts. These needles co-operate with frame needles in knitting a roll welt and rib fabric. Rib loops are transferred from machine needles to frame needles preparatory to knitting plain on the latter only.

This invention appertains to straight-bar knitting machines of the Cotton's patent or similar type for producing outer garments and the like.

Such knitted garments are customarily mainly plain knitted but provided at their lower ends with rib borders or welts.

Heretofore, it has been the more common practice to separately produce rib knitted borders or welts in strings, with waste courses and draw threads between them, on a flat rib knitting machine. Then, after separation of the rib borders or welts from the string, by removal of the draw threads, the terminal course of loops of each border or welt are initially placed upon or picked up by individual points of a rib transfer bar. The loaded transfer bars are then systematically placed upon a combined bar conveyor and feed apparatus which is mounted upon a straight-bar knitting machine is so constructed and operable as first to convey the loaded bars longitudinally along the machine to the relevant heads or divisions and then to deliver the said bars into corresponding rib transfer saddles. After advancement of each saddle towards the corresponding needle bar, the loaded rib transfer bar is moved to transfer the terminal course of loops of rib knitting on to the frame needles preparatory to the production on the latter of plain knitting in continuation of the rib knitting. The saddle is thereupon retracted and the now empty rib transfer bar is returned to its starting position by the bar conveyor and feed apparatus.

It will accordingly be appreciated that the continuous production of garments is dependent to some extent on the continuous supply of loaded transfer bars for placing upon the bar conveyor and feed apparatus, after the empty transfer bars have been removed therefrom.

But in order to obviate the necessity for rib borders or welts to be separately produced on another machine, it has already previously been proposed to provide a straight-bar knitting machine of a form adapted to pro-

2

duce both rib and non-rib fabric and having the facility to automatically change from rib knitting to plain knitting, as occasion demands. A machine of this form is equipped with a complete set of vertical "frame" needles selected ones of which can be withdrawn or otherwise rendered inoperative for rib knitting, and a set of horizontal "machine" needles which can be positioned in the spaces vacated by the selected and thus inoperative frame needles and are adapted for co-operation with the remaining, i.e. operative, frame needles during such rib knitting, provision being made in the machine for automatically transferring loops from the horizontal machine needles to the said selected frame needles as the latter are advanced and said machine needles are retracted preparatory to plain knitting on vertical frame needles only.

The present invention has reference exclusively to straight-bar knitting machines of the form just defined, and the primary object of the invention is to provide, in 20 or for such a machine, a generally improved machine needle having certain advantages hereinafter to be described.

Another object of the invention is to provide, in conjunction with a set of the improved machine needles, 25 a frame needle bar of generally improved form.

The machine needles constituting this invention comprise an outer element having a yarn-receiving and loop forming hook at its operative end, and a pair of inner loop-retaining elements which are longitudinally movable 30 together and relatively to the outer element and are adapted (a) by suitable operation thereof during rib knitting, to close the hook and guide an old loop retained by the inner elements over the hook to the point where the said loop is released and cast off the needle and (b) by advancement during transfer of loops to the selected frame needles to be engaged by the hook and as a consequence laterally separated and splayed apart to spread and open out a loop to be transferred.

The reason for laterally spreading and thereby opening 40 out a loop on the machine needle is, of course, to facilitate its penetration by a receiving frame needle.

The outer element may conveniently be fashioned from 45 a length of tubing of a flattened section and be so formed as to have a partly channelled and partly tubular shank adapted to accommodate and provide adequate guidance for the two inner loop-retaining elements assembled closely side by side within the shank.

Each of the two inner elements may conveniently consist of a straight and elongated flat blade the operative 50 end of which is rabbeted to form both a loop-retaining nose, rounded at its free end or tip and an adjoining loop-engaging shoulder. The free end portion of the loop-retaining nose of each of the inner elements is laterally offset by virtue of being inclined outwardly with respect to the straight blade. Apart from the fact that the two inner elements of the machine needle are opposite-hand, i.e. their laterally offset tips are respectively right-handed and left-handed, the said elements are identical in form.

In accordance with an important aspect of this invention 60 all three elements of the improved machine needle are mounted in a common bar wherein the pair of loop-retaining blades are slidably relatively to the hooked outer element.

Another feature of the present invention resides in the 65 provision, for use in conjunction with a bar of the improved machine needles, of a bar of wholly straight frame (vertical) needle the selected, e.g. alternate, ones of which are slidably mounted for movement up and down. Thus, for rib knitting, the said selected frame needles are withdrawn and rendered inoperative by virtue 70 of being slid down, whereas for plain knitting the same

needles are restored into their operative positions by being slid upwardly.

In order that the invention may be more clearly understood and readily carried into practical effect, a specific example of the improved machine needle, the common bar in which the outer and inner elements of such needles are mounted, the means for actuating the said elements and the manner in which the improved machine needles are operated for different purposes in conjunction with frame needles will now be described with reference to the accompanying drawings, wherein,

FIGURES 22-37 inclusive together constitute a sequence of detail views illustrating successive stages in the knitting of a roll welt by co-operation of the improved composites machine needles with nonslidable frame needles and sinkers, as will be hereinafter described,

FIGURES 38-42 inclusive are similar detail views depicting progressive steps in the knitting of rib fabric, and

FIGURES 43-50 inclusive illustrate successive stages in the transfer of rib loops from machine needles to slideable frame needles preparatory to plain knitting on frame needles only.

Like parts are designated by similar reference characters throughout the drawings.

The composite horizontal machine needle illustrated in FIGURES 1-12 comprises an outer element, generally

designated by the letter A, having a yarn-receiving and loop-forming hook 2 at its operative end, and a pair of left-hand and right-hand inner loop-retaining elements respectively designated B and B¹. The outer element A is fashioned from a length of tubing of the flattened section portrayed in FIGURE 5, and is so formed as to have a channelled shank portion 3 and a tubular shank portion 4. The two adjoining portions 3 and 4 of the shank provide guidance for the two inner elements B and B¹ assembled side by side within the said shank.

The operative hooked end of the shank is forwardly and downwardly inclined somewhat so that the underside of the hook 2 is below the lower straight edge 5 of the shank.

As shown more clearly in FIGURES 6 and 7, the portion 6 of the shank of the outer element A immediately behind the hook 2 is also of channelled form, by reason of the initially tubular shank being longitudinally slotted at this location, the upper edges of the spaced walls 6a of the channel 6 being upwardly shaped to provide a rounded belly formation 7 in the nature of a "hump" designed to maintain separated from one another a new loop in the hook and an old, i.e. previously formed, loop retained by the operative ends of the side-by-side inner elements B and B¹.

The tail end of the outer element A is furnished with an operating butt 8 for engagement in a cam-operated actuating bar 9 common to the outer and the inner elements of a series of the improved machine needles. Preferably, and as shown, this operating butt 8 extends downwards at right angles to the shank of the outer element A.

Each of the two inner loop-retaining elements B and B¹ consists, as illustrated in FIGURES 8-12, of a straight and elongated flat blade 10 the operative end of which is rabbeted at 11 (see FIGURE 10) to form both a loop-retaining nose 10a, rounded at its free end or tip, and an adjoining loop-engaging shoulder 10b.

That is to say, the loop-engaging shoulder 10b immediately adjoins the opposite end of the nose 10a. This shoulder 10b, preferably in the form of a forwardly inclined edge, adjoins the top edge of the loop-retaining nose, through a radiused portion 10c of the blade. The free end portion of the loop-retaining nose 10a of each of the inner elements B and B¹ may, if desired, be reduced in thickness somewhat although this is by no means essential.

In any event, the said free end portion of the nose 10a is laterally offset by virtue of being inclined outwardly with respect to the straight blade 10. The laterally offset end portion of the nose 10a of the element B of each pair of inner loop-retaining elements inclines to the left whereas, of course, the corresponding offset portion of the nose of the companion element B¹ inclines to the right. At its tail end each loop-retaining element is formed with an operating butt 12 adapted to be acted upon by a further cam-operated actuating bar 13 common to a series of machine needles (see FIGURES 13 and 17). In the specific example illustrated, the two side-by-side operating butts 12 of the pair of inner elements B and B¹ extends upwardly through the open top of the elongated channel 3 constituting the rear end portion of the straight shank of the outer hooked element A. This arrangement accordingly permits of free and relative longitudinal sliding movement between the outer element A and the pair of inner elements B and B¹.

The tubular portion 4 of the shank of the outer element A, which is intermediate the opposite ends of the composite machine needle, is relied on to retain the inner elements B, B¹ within the said outer element. As will be appreciated, at the location of the portion 4, the tube from which the outer element is fashioned is left wholly intact, thereby providing a complete encasement and fully embracing guide from the pair of inner elements.

The upper edges 10d of the loop-retaining noses 10a of the inner elements are below, i.e. of a less height than, the rounded belly formation 7 of the hooked outer ele-

ment A. Moreover, with the hook 2 open to receive yarn, the opposite-handed laterally offset tips of these noses are disposed behind the free end of the hook and just in front of the said rounded belly formation. When, however, the outer element A is retracted slightly the throat opening into the hook 2 becomes bridged and thus closed by the loop-retaining noses 10a of the inner elements B and B¹ and the hook rests with its upper free end in the V-shaped space S (FIGURE 2) between the opposite-handed laterally offset nose tips. When, on the other hand, the inner elements B and B¹ are advanced, during a loop-transferring operation, to the point where their nose tips are in front of the hook 2, as described in FIGURES 1 and 2, then the said hook automatically engages between and forcibly separates the leading ends of the inner elements.

As previously mentioned, all three elements of the improved machine needle are mounted in a common bar 9 which serves as an actuating bar for advancing and retracting en bloc the outer elements A of a series of the needles. The bar 9 and the aforementioned actuating bar 13 for action on the two sets of operating butts 8 and 12 respectively are arranged to be operated from rotary cam means driven either from the main cam shaft or from a lay shaft driven from the main cam shaft or from a lay shaft driven from the main cam shaft of a straight-bar knitting machine—through intermediate connections of any suitable character. Thus, referring to FIGURES 13, 17, 18 and 19, it will be seen that the actuating bar 9 is supported by carrier arms 14 which extend laterally from opposite ends of the said bar and are rigidly secured upon a pair of rearwardly directed and parallel spaced rods 15. These rods are mounted for longitudinal sliding movements back and forth through bearings 16 provided in side frame members 17 of a carriage. A pin 18 projects up from each of the two rods 15. Extending immediately beneath and at right angles to the two spaced rods 15 is a longitudinally displaceable shaft 19 (non-rotatable) which is slidable through bearings 20 provided in brackets 21 carried by or integral with the side frame members 17. At a location beneath each rod 15 is a linear cam 22 which is rigidly mounted on, and thus longitudinally displaceable together with, the shaft 19. In each of these two linear cams is formed an appropriately profiled slot 22a in which is engaged a roller 23 carried on the underside of a forked arm 24. Each arm 24 is provided at 25 upon a fixed part (not shown) and its bifurcated free end 24a engages the pin 18 projecting up from the corresponding rod 15. Accordingly, by shifting the shaft 19 to and fro, under cam control, the two forked arms will be simultaneously turned to move the rods 15, and hence also the actuating bar 9 carried thereby, back and forth, according to knitting requirements. For imparting the necessary to and fro movements to the shaft 19 there is provided a longitudinally shiftable actuating bar 26 which is combined with the said shaft in the manner depicted in FIGURES 18 and 19. The bar 26 is movable to and fro by a two armed lever 27 which is mounted to rock about a spindle 28 and carries at its lower bifurcated end a cam roll or truck 29 located between the suitably profiled peripheries of opposed operating and counter cams 30 and 31 respectively. There are, in fact, three operating cams 30, 30¹ and 30¹¹ arranged side by side and having respectively different profiles, the truck 29 being displaceable laterally in a selective manner for engagement by any one of the three operating cams, depending upon the desired motion to be imparted to the bar 9. Similarly, there are three corresponding counter cams. The said operating cams 30, 30¹ and 30¹¹ are rigidly secured upon a cross shaft 32 arranged to be driven from a shaft 33 through the medium of bevel gearing 34, 35 (FIGURE 18).

As shown in the last mentioned figures, the truck 29 is engaged by a fork 36 slidable along a rod 37 by controlled means (not shown) of any suitable character.

In a somewhat similar way, the actuating bar 13 is supported by carrier brackets 38 which are rigidly secured upon a pair of parallel spaced rods 39 disposed above and parallel to the aforementioned rods 15. The rods 39 slide back and forth through bearings 40 provided in the side frame members 17. A pin 41 projects up from each of the rods 39. At right angles to and below the two rods 39 is a non-rotatable shaft 42 which is displaceable longitudinally through bearings 43 provided in brackets 44 carried by or integral with the side frame members 17. Beneath each rod 39 is a linear cam 45 which is rigidly mounted on, and thus longitudinally displaceable together with, the shaft 42. In each of the cams 45 is formed a profiled slot 45a in which is engaged a roller 46 carried on the underside of a forked arm 47. Each arm 47 is pivoted at 48 upon a fixed part (not shown), and its bifurcated free end 47a engages the pin 41 projecting from the corresponding rod 39. Thus, by shifting the shaft 42 to and fro, under cam control, the two forked arms 47 will be turned to move the rods 39, and hence also the actuating bar 13 carried thereby, back and forth. For moving the shaft 42 to and fro there is provided an actuating bar 49 (see FIGURE 18) which is associated with the said shaft. The bar 49 is movable to and fro by a rocking lever 50 mounted to turn about the spindle 28. The bifurcated lower end of the lever 50 carried a truck 51 located between the peripheries of opposed operating and counter cams. There are three such operating cams 52, 52¹ and 52¹¹ arranged side by side and having respectively different profiles, the truck 51 being displaceable laterally for engagement by a selected operating cam. There are also three corresponding counter cams (not shown). The operating cams 52, 52¹ and 52¹¹ are rigidly secured upon the cross shaft 32 arranged to be driven as hereinbefore described. The truck 51 is engaged by a fork 53 slidable along the rod 37. The upper end of each of the two rocking levers 27 and 50 is forked in planes at right angles for sliding engagement with pivoted blocks pb provided at opposite sides of the bars 26 and 49 respectively.

In addition to the relative longitudinal sliding movements imparted to the outer and the inner elements of the machine needles, the common bar 9 housing a series of the latter may advantageously be so mounted and controlled by a rotary cam, e.g. on the main cam shaft, as to be movable up and down in the arcuate path designated ap in FIGURE 13. To facilitate such arcuate movements, the entire carriage of which the side frame members 17 form parts is mounted for rocking movement up and down about the axis of a shaft 54. The purpose of these additional arcuate movements are (i) to improve conditions for selvedging on both the frame and the machine needle bars and (ii) to facilitate control of the elements of the machine needles when forming a roll tip at the commencement of a rib knitted border or welt.

In FIGURES 13, 20 and 38-42 the reference numeral 55 indicates a conventional machine needle bar knock-over blade.

For use in conjunction with the bar 9 of the improved machine needles there is provided, in the illustrated example of the invention, a bar 56 of vertical frame needles 57 the alternate ones 57¹ of which are slidably mounted for movement up and down. For rib knitting, the sliding frame needles 57¹ are slid down to the inoperative positions shown in FIGURE 16, whereas for plain knitting, the said needles are slid upwardly again into their operative positions. The frame needles 57 are fixed in the bar 56, whilst the sliding needles 57¹ are mounted in a vertically displaceable component 58 slidably mounted in said bar. This component 58 is connected to pairs of toggle links 59, 60 which are arranged to be straightened to raise the sliding needles 57¹ and "broken" to lower the said needles by means of a longitudinally shiftable common bar 61. An operating lever 62 pivoted at 63 and forked at its upper end for engagement with a pin 64 on the bar 61 is provided for shifting the latter alternately rightwards

and leftwards. The lever 62 is connected with operating mechanism (not shown) through the medium of connections including a link 65.

The reference numeral 66 designates conventional sinkers for sinking loops around the frame needles.

The conjoint operation of frame and machine needles to produce a roll welt will now be described with reference to FIGURES 22-37 of the drawings.

Thus, in FIGURE 22, the vertical frame needle 57 is raised and the sinker 66 is advanced to sink a loop s^1 and draw yarn y around the stem of the said needle in the form of a new needle loop nl^1 —below the open spring beard 57a thereof. The old loop around the stem of the frame needle 57 is indicated at ol^1 . At this first stage in the sequence, the outer element A of the machine needle is advanced and empty, whilst the leading extremities of the two inner loop-retaining elements B and B¹ are behind the rounded belly formation, i.e. the hump, 7 and their shoulders 10b are approximately level with a shoulder 4a constituted by the leading end of the tubular shank portion 4 of the outer element.

At the next stage illustrated in FIGURE 23, the outer and inner elements of the machine needle are in the same positions as shown in FIGURE 22, but the frame needle 57 is in the course of being retracted in the knitting of a plain course.

In FIGURE 24, the said inner and outer elements A and B, B¹ of the machine needle are in the same relative positions as in FIGURES 22 and 23 but all three are slightly retracted. The beard 57a of the frame needle 57 has already been pressed by the presser edge 67, and the new loop nl^1 is in the course of being drawn by the same needle through the old loop ol^1 whilst the latter is about to be knocked over.

At the next stage shown in FIGURE 25, the inner and outer elements of the machine needle are still in the same relative positions but are retracted to a slightly further extent so that the hook 2 of the outer element A is about to catch and receive the loop s^1 from the neb 66a of the sinker 66 now being retracted. The inner elements B and B¹, however, are just about to be advanced relatively to the outer element A. The frame needle 57 is still in the course of being retracted to knock-over point.

In FIGURE 26 the sinker 66 has been withdrawn, and the needle 57 fully retracted to knock-over point. As a consequence, the freshly formed loop s^1 has dropped off the sinker neb 66a and been caught in the hook 2, whereas the old loop ol^1 is knocked over. Moreover, the inner elements B and B¹ of the machine needle have been further advanced relatively to the outer element A such-wise as to close the hook 2 of the latter.

At the subsequent stage depicted in FIGURE 27, the frame needle 57 has been raised again towards the draw position to receive a new length of yarn preparatory to commencement of the next draw. The outer elements A have been advanced towards the pressure edge 67 and inner elements B, B¹ have been retracted slightly together from the pressure edge 67, although the relative positions of the said elements are at this stage the same as in FIGURES 22 and 23. What was the new needle loop nl^1 has now become an old loop designated ol^1 .

In FIGURE 28, the fixed frame needle 57 is fully raised, and a loop s^1 is sunk for a new course, the yarn being again drawn around the stem of the frame needle in the form of a loop nl^1 . The machine needle, on the other hand, is still in its advanced position—with the inner elements B and B¹ drawn back into the outer element A and the loops behind the hump 7.

Thereafter, as depicted in FIGURE 29, the frame needle 57 commences to retract and its beard 57a to be pressed by the presser edge 67, whereas the machine needle, still carrying the loop s^1 behind the hump 7 is about to be retracted away from the presser edge 67.

In FIGURE 30, the beard 57a of the frame needle 57

has already been pressed again and this needle has commenced to draw the loop nl^1 through the old loop ol^1 . The outer element A has been retracted away from the presser edge 67, leaving the inner elements B and B¹ in the same position as before. As a consequence of these motions, the loop s^1 is in front of the hump 7.

At the stage in the cycle shown in FIGURE 31, the frame needle 57 is in the course of being retracted to knocking-over position, the latest loop nl^1 to be formed by the said needle being drawn through the old loop ol^1 which latter is shown as actually knocked over. The outer element A of the machine needle is now in its fully retracted position so that the inner elements have completed closure of the hook 2 and the loop s^1 is retained in the hook of element A. At this stage loop s^1 is about to fall off sinker neb 66a and miss the hook portion of element A.

In FIGURE 32 the frame needle 57 is rising to draw position, and the new loop designated nl^1 in FIGURE 31 has become the old loop ol^2 now around the stem of the said needle. The outer and the inner elements of the machine needle both advance but the outer element A to a greater extent than the two inner loop-retaining elements B and B¹ so that at this stage the shoulders 10b on these elements are once again level with the shoulder 4a at the leading end of the tubular shank portion 4. As a consequence, the loop s^1 released by the retracting sinker becomes located under element A.

It is to be understood that in practice the stages illustrated in FIGURES 28-32 inclusive are repeated for a plurality, e.g. four or five, courses to produce the roll welt. Thereafter, the sequence continues in the manner depicted in FIGURES 33-37 which, for convenience will now be described without, however, the intervening roll welt courses being shown.

Thus, in FIGURE 33, the needle 57 has received yarn and, by advance of the sinker 66, a sinker loop s^2 has been formed and an adjoining new needle loop nl^2 drawn around the stem of the said needle. The machine needle, on the other hand, is in exactly the same position as in FIGURE 32.

At the next stage shown in FIGURE 34 the beard 57a of the frame needle 57 has already been pressed, and the outer element A of the machine needle is being retracted slightly to be in a position to accept the freely formed loop s^2 off the sinker neb 66a: in fact, as a consequence of retraction of the sinker 66, this loop s^2 is shown sliding along and down the neb 66a preparatory to falling into the hook 2 of the outer element A—at the hook side of the hump 7. The old loop s^1 at the other side of the hump 7 is that caught in the hook 2 in the first course of the roll welt. In FIGURE 34, moreover, the inner elements B and B¹ are commencing to move forward slightly relatively to the outer element A.

The stage depicted in FIGURE 35 is similar to that shown in FIGURE 34, except that the loop s^2 is in the course of actually falling into the hook 2. The outer element A is being retracted as the inner elements B and B¹ are being still further advanced to close the hook 2, with the loop s^2 therein, and to collect the old loop s^1 preparatory to it being knocked-over. The frame needle 57, having thereon the old loop ol^2 , is being retracted towards knock-over point.

At the stage illustrated in FIGURE 36, both the frame needle 57 and the machine needle have knocked-over to complete the roll welt. That is to say, the old loop ol^2 has been knocked-over, and the loop which was previously the loop nl^2 is now the old loop ol^3 . The loop s^1 has been knocked-over and the loop s^2 is in the closed hook 2.

In FIGURE 37, the outer element A is advancing towards the presser edge 67 with the inner elements B and B¹ retracted to the point where the shoulders 10b are substantially coincident with the aforementioned shoulder 4a. The frame needle 57 is advancing towards the draw

position preparatory to commencement of the next rib course.

A sequence for rib knitting will now be briefly described with reference to FIGURES 38-42. At the stage illustrated in FIGURE 38, an old loop o^3 as in FIGURE 37 is on the stem of the frame needle 57 below the beard 57a thereof, and an old loop s^2 as in FIGURE 37 on the machine needle is located against the shoulder 4a of the outer element A. The frame needle is raised to draw position.

At the next stage shown in FIGURE 39 the frame needle 57 having been raised to draw position is now moving in and down towards the presser edge 67. The inner and outer elements of the machine needle are in precisely the same positions as in FIGURE 38. The sinker 66 is retracting, so that there is a new loop nl^3 around the stem of the frame needle 57 and a new sinker-formed loop s^3 .

FIGURE 40 portrays a situation somewhat similar to that shown in FIGURE 35 of the roll welt sequence, the difference being that the new sinker-formed loop s^3 is shown caught in the hook 2 of the outer element A whilst the old sinker-formed loop s^2 is behind the hump 7 of the said outer element; that is to say, this hump is shown assisting in separation of the loop s^2 from the loop s^3 . At this stage the new loop nl^3 is being drawn through the old loop o^3 .

At the next stage shown in FIGURE 41, the frame needle 57 is in the process of knocking-over, whereas the new sinker-formed loop s^3 is being guarded by the inner elements B and B¹ which are advanced to close the hook 2, thereby completing separation of the loops s^3 and s^2 and also moving the latter towards the point where it is knocked-over by suitable actuation of the machine knock-over blade 55.

In FIGURE 42, both the frame and the machine needles have completed knock-over. Immediately thereafter, the outer element A of the machine needle is advanced to the position indicated in FIGURE 38, and the cycle is repeated the required number of times to give the necessary length of rib fabric before transferring to plain knitting.

A transfer sequence from rib knitting to plain knitting is illustrated in FIGURES 43 to 50 and will now be described.

First the yarn carrier is disengaged from the draw as a consequence of which no yarn is laid during this sequence. Referring to FIGURE 43 it will be seen that the frame needle 57 is moving down past but clear of the presser edge 67, i.e. without its beard 57a being pressed. Moreover, at this stage the previously inactive frame needles such as that indicated at 57¹ commence to rise. The composite machine needle, having been advanced from the position shown in FIGURE 42, is near the said presser edge so that the loop s^4 is against the shoulder 4a of the outer element A. An old loop o^4 is around the stem of the needle 57 below the beard.

In FIGURE 44, the beard 57a of the frame needle 57 is seen missing the presser edge 67 to enable the loop o^4 to move up into the eye of the said needle. The outer element A of the machine needle is commencing to retract—with the inner elements B and B¹ moving forward in order that they may collect the loop s^4 . The previously inactive slideable frame needle 57¹ advances, i.e. rises, at the same rate as the frame needle 57 (which is fixed in the frame bar) descends.

At the stage shown in FIGURE 45, the inner and the outer elements of the machine needle are in the same positions as in FIGURE 44, but the frame needle 57 has moved further down past the presser edge 67.

During the successive stages portrayed in FIGURES 45-49 inclusive, the inner elements B and B¹ displace the loop s^4 and move it over the hook 2 of the outer element A of the machine needle in readiness for transfer of this loop to the rising sliding frame needles 57¹. Thus, in FIGURE 49, the loop-retaining noses 10a of the

advancing inner elements B and B¹ have been spread laterally by the hook 2 of the outer element A as a consequence of which the loop s^4 has been opened out for easy penetration by the still rising slideable frame needle 57¹. In FIGURE 50, the frame needle 57¹ has received the loop s^4 and the machine needle has retired by virtue of the machine needle bar moving out of operation. As the frame needle 57¹ thereafter advances past threading up position, the loop s^4 will slide below the beard of that needle. This completes the transfer sequence, so that the spaced fixed frame needles 57 and the intervening slideable frame needles 57¹ can now act together as a complete set of frame needles operable to produce plain fabric.

As will be appreciated from the foregoing description the composite machine needles are so constructed that they can carry out their necessary knitting motions without the need either for beards and pressers or latches.

The improved form of composite machine needle is advantageous in that it ensures good loop penetration by the loop-retaining blades, even at selvedge edges, during rib knitting for the reason that the loop to be penetrated is securely supported and held across the channelled throat of the hooked outer element. By being supported in this way the loop is held open for the easy entry thereto of the noses of the loop-retaining blades.

Use of the improved machine needles, moreover, enhances the quality range. Again, because the loop-engaging shoulders on the loop-retaining blades are of fair length (heightwise), the "take-off weight" for drawing down the fabric does not have to be critically relied upon to maintain the engagement with these shoulders of loops in the course of being transferred to frame needles. In addition, the improved needle construction makes for reliable transfer of loops from machine needles to frame needles inasmuch as the lateral expansion of these loops by the forcibly separated blades provides adequate room for penetration of the loops by eyes of the frame needles. Finally, by virtue of all the elements of the machine needles being mounted and supported in a common bar, a particularly strong construction is achieved.

We claim:

1. A straight-bar knitting machine of a form adapted to produce both rib and non-rib fabric and having the facility to automatically change from rib knitting to plain knitting, as occasion demands, said machine comprising a set of vertical frame needles, means for rendering inoperative selected ones of said needles for rib knitting, a set of horizontal machine needles which can be positioned in the spaces vacated by the selected and thus inoperative frame needles for co-operation with the remaining and operative frame needles during such rib knitting, means supplying yarn to the needles; means operating the needles so that they take yarn and form it into knitted loops; and means for automatically transferring loops from the horizontal machine needles to the said selected frame needles as the latter are advanced and said machine needles are retracted preparatory to plain knitting on vertical frame needles only, and wherein the improvement resides in the provision in such a machine of horizontal machine needles each comprising an outer element having at its operative end a yarn-receiving and loop-forming hook and also having an operating butt, and a pair of inner loop-retaining elements which are longitudinally movable together and relatively to the said outer element for closing the hook of the outer element and guiding an old loop retained by the inner elements over the hook for casting-off during rib knitting, and for advancing into engagement with the said hook to be laterally separated and splayed apart by the hook during transfer of loops to the selected frame needles, whereby to spread and open out a loop to be transferred, said inner elements being formed with side-by-side operating butts; a first actuating bar common to all the machine needles and for acting on the butts of the outer elements

11

for the purpose of moving same; cams for operating said first actuating bar; a second actuating bar also common to all the machine needles but for action on the butts of the inner elements for the purpose of moving the latter and further cams for operating said second actuating bar.

2. A straight-bar knitting machine according to claim 1, wherein the outer element of each horizontal machine needle has a partly channeled and partly tubular shank accommodating and providing guidance for the two inner loop-retaining elements assembled closely side by side within the shank.

3. A straight-bar knitting machine according to claim 2, wherein the operative hooked end of the shank of the outer element of each of the horizontal machine needles is forwardly and downwardly inclined so that the underside of the hook is below the lower straight edge of the said shank.

4. A straight-bar knitting machine according to claim 3, wherein in regard to each horizontal machine needle the portion of the shank of the outer element immediately behind the hook is of channeled form, the upper edges of the spaced walls of the channel being upwardly shaped to provide a rounded belly formation in the nature of a "hump" designed to maintain separated from one another a new loop in the hook and an old (previously formed) loop retained by the operative ends of the side-by-side inner elements.

5. A straight-bar knitting machine according to claim 1, wherein the operating butts of the outer elements of the machine needles are provided at the tail ends of the said elements and extend downwardly for engagement in the first actuating bar.

6. A straight-bar knitting machine according to claim 1, wherein each of the two inner elements of each of the horizontal machine needles consists of a straight, elongated flat blade the operative end of which is rabbetted to form both a loop-retaining nose and an adjoining loop-engaging shoulder.

7. A straight-bar knitting machine according to claim 6, wherein the loop-engaging shoulder of each of the two inner elements of each of the horizontal machine needles is in the form of a forwardly inclined edge which adjoins the top edge of the loop-retaining nose through a radiused portion of the blade.

8. A straight-bar knitting machine according to claim 6, wherein the free end portion of the loop-retaining nose of each of the two inner elements of each horizontal machine needle is laterally offset by virtue of being inclined outwardly with respect to the straight blade, and the said elements are opposite-handed, i.e. with their laterally offset portions respectively right-and-left-handed.

9. A straight-bar knitting machine according to claim 2, wherein two side-by-side operating butts on the pair of inner elements of each horizontal machine needle extend upwardly through an open top of an elongated

12

channel constituting the rear end portion of the shank of the outer hooked element of the needle.

10. A straight-bar knitting machine according to claim 9, wherein the said side-by-side butts extend upwardly from the tail ends of the inner loop-retaining elements and are engaged in the second actuating bar.

11. A straight-bar knitting machine according to claim 4, wherein upper edges of loop-retaining noses on the inner elements of each horizontal machine needle are below and of a less height than the rounded belly formation of the hooked outer element of the said needle.

12. A straight-bar knitting machine according to claim 8, wherein with the hook of outer element of each horizontal machine needle open to receive yarn, the opposite-handed laterally offset portions of the noses of the corresponding pair of inner elements are disposed behind the free end of the hook and in front of the rounded belly formation, but when the outer element is slightly retracted the throat opening into the hook becomes bridged and thus closed by the loop retaining noses and the hook rests with its said free end in a V-shaped space between the aforesaid opposite-handed laterally offset portions.

13. A straight-bar knitting machine according to claim 1, wherein all three elements of each of the horizontal machine needles are mounted in the first actuating bar in which the pair of loop-retaining blades are slideable relatively to the hooked outer element of the needle, the first and second actuating bars for action on the two sets of operating butts being arranged to be operated from rotary cam means driven from a main cam shaft of the machine.

14. A straight-bar knitting machine according to claim 13, wherein the said common bar is so mounted, and controlled by a cam, as to be movable up and down in an arcuate path, for the purpose specified.

15. A straight-bar knitting machine according to claim 1, wherein the vertical frame needles are mounted in a bar and selected ones of said needles are slidably mounted for movement up and down together.
